OPEN-FACED RACK

Samuel S. Schiffer, New York, N. Y.

Application December 26, 1950, Serial No. 202,726

1 Claim. (Cl. 211—50)

1

The instant invention relates to book, magazine and paper racks and more particularly to such a rack in which the items supported tend to assume a stable position.

One of the primary objects of the invention is the construction of a rack of the character indicated embodying in various modifications a basic unit or trough having three sides, each of which sides in operative position is disposed at an angle to both the vertical and the horizontal.

Yet another aim of the invention is the formation of a rack or tray of the type above referred to which will serve to support items filed in a manner to inhibit falling down or curling up of same; which in the case of books, magazines and the like will permit removal or replacement of abutting items without disarranging the remainder and which will further support the books or magazines so that the titles of same are readily visible.

Still a further purpose is to provide a rack which is simple in construction; which may be made at relatively small cost and in which the principle of the invention may be embodied in several distinctive forms.

The above and other aims and objects will be apparent from the detailed description herein-after appearing when taken in conjunction with the appended drawings forming a part hereof to which attention is directed and in which:

Fig. 1 is a front elevational view of the magazine or book rack embodying the invention;

Fig. 2 is a side elevational view looking to the left in Fig. 1;

Fig. 3 is a perspective view of the rack of Figs. 1 and 2 showing magazines and the like supported in operative position thereon;

Fig. 4 is a perspective view of a modification comprising a multiple rack unit serving as filing cells for letters, pamphlets or the like;

Fig. 5 is a front elevational view of a further modification in the form of a stand for a telephone and telephone directories; and

Fig. 6 is a side elevational view of the stand of Fig. 5.

Referring first to Figs. 1, 2 and 3, the rack R includes a trough or tray T comprising a rear or back wall 10, a base or bottom wall 11, and a lateral, end or side wall 12, resulting in a basic unit, which, in this instance is open at its forward and right hand sides. The three wall sections are connected one to the other, in any conventional manner, and each wall extends in a plane substantially at right angles to the plane of the other two wall sections, thus forming the corner 13.

2

Tray T has a supporting frame F which, as shown, takes the form of a unitary metal strap or the like 14, having a short downwardly curved leg 15, a long straight portion 16, a tall U-shaped leg section 17 and a short section 18. Straight portion 16 is secured to the under face 19 of bottom wall 11 as by screws, rivets or the like 20; similar fastenings 21 being used to attach short strap section 18 to the rear face of back wall 10. It will now be seen that the points of support for the tray T are (a) corner 13; (b) short leg 15; and (c) tall U-shaped leg 17. Consequently, each of walls 10, 11, and 12, is, when resting on a horizontal surface such as a floor, table or the like, angularly disposed to both the horizontal and vertical.

Turning now to Fig. 3, the advantages of the structure so far described will be apparent. A group of magazines, books or the like M, will tend to assume the position shown due to the inclination to the rear, as well as inclination to the left of bottom wall 11 on which the articles rest. If an intermediate one of the magazines or books is removed, the others are not disarranged; also the titles will be clearly visible with free access to same while supported in a neat stack.

In the modification of Fig. 4, a unit U having multiple cells c is illustrated and embodies the same inventive concept as heretofore described. This unit comprises a plurality of spaced parallel side walls 22, 22a, 22b, 22c, each of which has a bottom edge as at 23 which, in operative position, rests on a table, desk or the like. The reference characters 21, 21a, 21b, 21c represent bottom walls secured to the adjacent side walls 22, 22a, 22b, 22c, preferably by means of flanges, such as 22'. Finally, there is a unitary rear or back wall 20 secured to and common to all the side and bottom walls.

As will readily be seen, the bottom walls 21, 21a, 21b, etc. are in staggered relation to one another and each is inclined both rearwardly towards the common back wall 20 and to the left toward a side wall 22, 22a, 22b, etc. The multiple unit U thus formed finds application as a sorting or filing rack in which the cells c may receive and support papers, pamphlets, or the like with the same advantages inherent in the showing of Figs. 1, 2 and 3. The material used in forming this unit may be plastic in sheet form, in addition to other conventional materials; and it will be understood that the number of cells may be increased to any desired number by merely multiplying the side and bottom walls and enlarging the back wall 20.

Figures 5 and 6 show a telephone stand S which

may take any conventional shape and is provided with a tower portion 30 upon which a telephone may rest. A tray T' having the structural features of the tray T of Figs. 1, 2 and 3 is built into the stand and supported in a manner similar to the latter so that telephone directories and the like will assume the position of magazines M of the forementioned three figures with the advantages thereof.

From the above it will now be apparent that the objects and purposes of the invention have been attained, and it might be pointed out that it is not necessary that walls 10, 11 and 12, and the corresponding members in the other views be at right angles to each other, as small angular variation will not defeat the basic inventive concept. Various changes will be apparent to those skilled in the art and it is contemplated to cover all such and to be limited in this respect only as may be necessary by the scope of the claim 15 hereto appended.

What I claim and desire to secure by Letters Patent is:

An open-faced rack for papers or the like comprising a back wall, a plurality of spaced parallel 25

side walls connected to the latter, the lower edges of said side walls constituting supporting means for said rack, a plurality of bottom walls, each bottom wall having a pair of upturned side flanges connected to adjacent side walls, and being also connected to said back wall, each bottom wall further being inclined toward the rear wall and to a side wall which it connects, thus forming an open-faced rack having a plurality of cells in which a paper placed on a bottom wall of a cell will abut said back wall and a side wall.
